[57] **CLAIM**

The ornamental design for a bicycle derailleur, as shown and
described.

DESCRIPTION

FIG. 1 is a first side elevational view of a bicycle derailleur
showing my new design;

FIG. 2 is a front elevational view of the bicycle derailleur
showing my new design;

FIG. 3 is a rear elevational view of the bicycle derailleur
showing my new design;

FIG. 4 is a top elevational view of the bicycle derailleur
showing my new design;

FIG. 5 is a second side view of the bicycle derailleur
showing my new design; and,

FIG. 6 is a bottom view of the bicycle derailleur showing my
new design.

The drawings show a bicycle derailleur in accordance with
embodiments of my new design.
